UNITED STATES PATENT OFFICE.

CLYDE BAILEY, OF PENLAND, NORTH CAROLINA

RAILWAY-TIE.

1,085,841.

Specification of Letters Patent.

Patented Feb. 3, 1914.

Application filed January 2, 1913. Serial No. 739,916.

To all whom it may concern:

Be it known that I, CLYDE BAILEY, a citizen of the United States, residing at Penland, in the county of Mitchell, State of North Carolina, have invented certain new and useful Improvements in Railway-Ties; and I do hereby declare the following to be a full, clear, and exact description of the invention, such as will enable others skilled in the art to which it appertains to make and use the same.

The present invention relates to certain novel and useful improvements in railway ties and has particular application to a wooden tie provided with a metallic casing or sheathing.

In carrying out my invention, it is my purpose to provide an ordinary wooden tie with a sheathing of metal, whereby the life of the tie is greatly prolonged and at the same time is strengthened so as to resist the wear and tear and shocks and jars ordinarily incident to the travel of the rolling stock over the road. By the use of this sheathing, the wooden portion of the tie is further protected against deteriorations due to exposure to the elements. Furthermore, it is my purpose to provide a tie which embraces in the present instance a pair of wooden blocks connected together and incased by a single sheathing of metal, the meeting edges of the latter lying at the under side of the tie when such tie forms a part of the roadway.

With the above recited objects and others of a similar nature in view, my invention consists in the construction, combination and arrangement of parts set forth in and falling within the scope of the appended claim.

In the accompanying drawings:—Figure 1 is a perspective view of a section of railway provided with my improved tie. Fig. 2 is a longitudinal sectional view taken through the tie and the rails connected thereto.

Referring now to the accompanying drawings in detail, the numerals 1—1 designate the ordinary railway rails and in Fig. 1 I have shown one of the rails provided with the usual fish plates or rail joint plates 2.

My improved tie is indicated as an entirety by the letter A, and is composed of

a pair of wooden blocks 3—3, preferably trimmed or cut into octagonal form. These blocks are connected and incased by the metallic sheathing 4, the latter being preferably made of a single sheet of metal bent into tubular form, the tube being approximately octagonal in cross section to conform to the shapes of the blocks. These blocks 3 are inserted in the casing of sheathing from the ends of the latter, one block being inserted of course in each end.

When in use, the rails are placed across the tie in the usual manner and are secured thereto through the medium of suitable spikes 5 which are driven through the upper surface of the sheathing and through the body of the tie directly therebeneath, the heads of the spikes clamping the edges of the rail in the usual manner as clearly shown in the drawings.

It is to be noted that the slot 6 formed by the meeting edges of the casing or sheathing when the latter is bent into tubular form, is designed to lie at the under side of the wooden end blocks so that the entrance of moisture is prevented. Furthermore, by bending the sheathing or casing into the form shown, it has a tendency to shed the water or direct the same away from the tie.

If desired, the ordinary bearing plates may be placed beneath the rails so as to rest upon the tie, the bolts in such instance passing directly through the plates and the tie, in the manner readily understood.

It will be noted that I have provided an exceedingly simple, yet efficient tie designed especially for use in localities subject to heavy rains, the sheathing preventing the tie from being rapidly destroyed by the severity of the elements.

What I claim is:—

A railway tie comprising a metallic sheathing of octagonal form in cross section, and correspondingly shaped wooden blocks inserted in the ends of the tie and incased by the sheathing.

In testimony whereof, I affix my signature, in the presence of two witnesses.

CLYDE BAILEY
